UNITED STATES PATENT OFFICE

RODNEY W. MARTIN, OF DAYTON, OHIO

CABINET KITCHEN

Application filed November 24, 1925. Serial No. 71,162.

My invention relates to camp kits and equipment and more particularly to a camp kitchen for use of tourists, campers and other temporary residents.

- 5 In the present invention there is contemplated a cabinet or housing, suitable to be carried on the running board of a motor vehicle and which may be temporarily elevated on a box, table or other convenient support.
- 10 It not only embodies compartments, shelves and containers for the usual camp cooking equipment, dishes and essentials, but contains independent compartments, each separately accessible from the exterior of the cabinet or housing. One of such compartments is for the reception of food and the other to enclose a stove and fuel. The construction and arrangement is such that the equipment and utensils may not only be compactly arranged
- 15 and easily accessible for use and safe for transportation, but they are entirely separated from the food compartment and from the stove and fuel compartment so that neither the equipment and utensils nor the
- 20 food supply may be contaminated by odors from the stove or odors of fuel. The food and stove compartments are readily accessible from the exterior of the cabinet, without the necessity of opening or disturbing the contents of the equipment and utensil compartment. The various compartment closures are so arranged and disposed that they may be utilized as tables or supports for various culinary operations. The main closure door
- 25 which extends beyond the equipment and utensil compartment and overlaps both the stove and food compartments is hinged at its bottom and when opened is supported in a horizontal position, by an adjustable supporting leg for use as a table for general purposes. The closure door of the food compartment is of greater extent than the access opening to such compartment, beyond which it extends when closed and is adapted when
- 30 opened to form an auxiliary leaf or support

for the disposition of food and cutting of bread and like operations. The closure door to the stove and fuel compartment is likewise adapted to form a rest or support for the camp stove and is provided with an extra leaf, which may be upturned to afford a wind break or protection to the stove against air currents or when not so used may be extended as an auxiliary table for culinary purposes.

50 The object of the invention is to simplify the structure, as well as the means and mode of operation of camp equipment cabinets, whereby they will not only be cheapened in construction, but will be more efficient in use, 55 convenient in arrangement, durable and unlikely to get out of repair.

60 A further object is to provide a camp cabinet, which will be of comparatively small size, in which the cooking and dispensing equipment may be closely and compactly arranged and which will embody entirely separated compartments for food and for the camp stove and fuel supply, which 65 various compartments are accessible independently from the exterior of the cabinet.

70 A further object is to provide a camp kitchen cabinet, the closure doors of which afford ample table area, greater than the areas of the compartment openings closed thereby.

75 With the above primary and other incidental objects in view as more fully appears in the specification, the invention consists of the features of construction, the parts and combinations thereof, the arrangement of the features, and the mode of operation, or their equivalents as hereinafter described and set forth in the claims.

80 In the accompanying drawings, wherein is shown the preferred, but obviously not necessarily the only form of embodiment of the invention, Fig. 1 is a perspective view of a camp cabinet forming the subject matter hereof. Fig. 2 is a similar perspective view 85 from the opposite side. Fig. 3 is a vertical

sectional view. Fig. 4 is a detail view of the closure door for the stove compartment.

Like parts are indicated by similar characters of reference throughout the several views.

The present camp kitchen or culinary cabinet is particularly designed for use of motor tourists, and is adapted to be carried on the running board of a motor vehicle. Obviously, however, when camping the cabinet may be supported upon any convenient stump, box, table or other support. Such cabinet will also be found a great convenience to temporary residents of summer camps or cottages, and other persons who have occasion to change their location or place of abode more or less frequently.

In the accompanying drawings, 1 indicates the running board of a motor vehicle, of which 2-2 are the front and rear fenders. The camp kitchen forming the subject matter hereof, comprises a housing or container of rectangular form, and box-like appearance, which is customarily formed of laminated veneer, fiber or other light but strong material. The cabinet 3 is divided into three entirely independent and separate compartments comprising the main equipment and utensil compartment 4, which faces forwardly, a food compartment 5 which opens to one side of the cabinet 3, and a stove compartment 6, which opens to the opposite side of the cabinet. The main compartment or utensil and equipment compartment 4 is provided with shelves 7 and 8, and with a drawer 9. This drawer 9 is preferably of such size that it will readily and easily receive a carton of eggs, and is preferably provided with a partition forming a separate compartment within the drawer 9 to receive silverware and small utensils, knives and the like. Hinged at each side of the main compartment 4 are swinging carriers 10 and 11, which may carry small containers for staple supplies, such as salt, sugar, tea, coffee and the like.

These carriers 10 and 11 being hinged to the cabinet structure are turned into the interior of the compartment 4, when the compartment is closed. Upon opening the cabinet, these carriers are turned outwardly, where they are more conveniently located and easily accessible, also leaving the shelves 7 and 8 and drawer 9 readily accessible. The various cooking utensils and dishes may be conveniently and compactly disposed within the compartment 4. A deep space 12 is provided intermediate the food compartment 5, and stove compartment 6, in which the larger pieces may be readily fitted. Hinged to the bottom of the front of the cabinet 3 is a large closure door 13 forming the front side of the housing which is considerably larger than the opening of the compartment 4, and overlaps the food compartment 5 and stove compartment 6, as well as forming a closure door

for the equipment and utensil compartment. This closure door 13 opens downwardly and forwardly about its hinge connection at its lower margin and is supported in horizontal position by an adjustable detachable leg 14, so that the enlarged closure door 13 may be utilized as a table. If such table was limited to the area of the compartment 4, it would be quite too small to be serviceable. However, by extending this closure door beyond the limit of the compartment for which it forms a closure and making the hinged closure door equal to the entire front side of the cabinet, including the area, not only of the compartment 4, but also the auxiliary food and stove compartments 5 and 6, this hinged closure door is made of ample size to serve as a general purpose table. Inasmuch as it is not desirable to have the general food articles intermixed with the utensils and cooking equipment and since easy access will be frequently desired to the food compartments as articles of food may be purchased from time to time, while traveling, this compartment 5 is provided with an entirely independent access opening, located in the side of the cabinet. The access opening of the food compartment is closed by a hinged closure door or lid 15 also connected to the cabinet at its lower margin and opening downwardly and outwardly. This closure door 15 for the food compartment 5 is also of greater extent than the access opening, and when closed extends a considerable distance above the openings to the food compartments within a frame or flange 16, formed upon the side of the cabinet. By thus extending the closure door 15, such door when opened to horizontal position is of ample size to serve as a cutting board for bread or other food articles and to be used as an auxiliary table. The propensity of many food articles to absorb odors and the danger of liquid fuel, such as gasoline or kerosene contaminating the food as well as the cooking equipment and utensils is guarded against by making the stove compartment entirely independent and separate from the food and utensil compartments. This stove compartment is located on the opposite side of the cabinet and opens outwardly. It is of sufficient size to contain a popular type of camp stove 17, which is operated by liquid fuel, such as gasoline or kerosene, alcohol, or the like, supplied from a tank 18. Like the closure doors for the main equipment compartment 4, and the food compartment 5, that of the stove compartment 6 is also hinged at its lower margin and opens downwardly and outwardly. When extended to horizontal position, it affords a support or table for the stove 17. The closure door 19 of the stove compartment is provided with an inwardly folding leaf or extension 20, hinged to its rear margin, and foldable to the interior of the door when the compartment is 130

closed. This leaf or extension 20 may be upturned to a substantially right angle position as shown in Figs. 1 and 2 to protect the side of the vehicle against excessive heat from the stove when the cabinet is employed upon the running board of the vehicle. Likewise, this leaf or extension 20 may be upturned when the cabinet is removed from the vehicle and supported upon a box or table in order to protect the stove from air currents. The same leaf or extension 20, may be turned horizontally as shown in Fig. 4 in which position it is supported upon an arm 21, pivoted to the outer side of the closure door 19, to form an auxiliary table for the support of food and utensils used about the stove 17. When removed from the running board of the vehicle, the closures 15 of the food compartment 5, and 19 of the stove compartment 6, may be supported upon detachable legs or props similar to that shown at 14. Such legs or props are adjustable in height to accommodate them to inequalities of the ground. At the top of the stove compartment 6 there is provided a ledge 22 having in it a series of holes 23 in which may be thrust sticks from which to suspend towels and dish cloths for drying.

The swinging carrier 11 overlaps the drawer 9 when closed and is clamped against the front of the drawer by the closure door 13 thus holding the drawer against movement. The cabinet or housing rests upon base rails or sills 24 in which is slidingly mounted an auxiliary leaf or shelf 25. The slide 25 is convenient for temporary use under conditions where it is not desired to open the main compartment. When the cabinet is removed from the running board of the vehicle and supported upon a table or box, this slide may be projected rearwardly to afford an additional shelf, when the closure 13 is in use as a table.

It will be apparent that the camp kitchen thus described affords a convenient, compact container for kitchen essentials and equipment as well as food articles and the camp stove, all of which are separated from each other, but readily accessible and that the closure doors for the cabinet are so arranged as to afford a maximum table area, materially greater than the area of the access openings of the several compartments, to which such closures pertain. The arrangement and relation of the several compartments and their extension doors is such that the cabinet is quite convenient for use, whether left in position upon the running board of a motor vehicle or removed therefrom to other suitable supports.

From the above description it will be apparent that there is thus provided a device of the character described possessing the particular features of advantage before enumerated as desirable, but which obviously is susceptible of modification in its form,

proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

1. In a camper's culinary cabinet and the like, a housing having therein a utensil and equipment compartment accessible from the front of the housing, a food compartment of less height than the housing accessible from one side of the housing, said compartment being located at the bottom of the housing with the utensil and equipment compartment extending above and at one side of said food compartment, and a stove compartment extending from the bottom to the top of the housing at one end thereof and accessible from the side of the housing, and independent closures for the respective compartments, including a double door for the stove compartment, the sections of which are normally disposed in overlapping relation with one section hinged to the other, and the latter section hinged at its lower margin to the housing, said food, stove and equipment compartments being non-communicating with each other, and a closure door for the equipment compartment hinged to the housing at its bottom and opening downwardly and forwardly to form a table, said closure door being of greater area than the access opening of the equipment compartment and extending therebeyond into overlapping relation with the food and stove compartments.

2. In a camper's culinary cabinet and the like, a housing divided into noncommunicating compartments comprising an equipment compartment of less height than the housing, located at one end thereof, a food compartment and a stove compartment located at the opposite end of the housing and extending from the bottom to the top thereof, each of said compartments extending from the front face to the rear of the housing, the food and stove compartments being spaced one from the other, with the equipment compartment located above said food compartment, and extending thence downwardly between the food compartment and the stove compartment, each independently accessible from a different side of the housing, the front side of

the housing commensurable with the combined areas of all the compartments being hinged to the housing at its bottom overlapping the several compartments when closed and opening downwardly and forwardly to form a table, and means for supporting the housing side when in extended position.

In testimony whereof, I have hereunto set my hand this 18th day of November, A. D. 1925.

RODNEY W. MARTIN.
